UNITED STATES PATENT OFFICE.

JAMES W. BRAINARD, OF PITTSBURGH, PENNSYLVANIA.

METAL HEAD FOR BARRELS OR KEGS.

1,273,997.

Specification of Letters Patent. Patented July 30, 1918.

Application filed March 8, 1916. Serial No. 82,853.

To all whom it may concern:

Be it known that I, JAMES W. BRAINARD, a citizen of the United States, residing at Pittsburgh, Allegheny county, Pennsylvania, have invented certain new and useful Improvements in Metal Heads for Barrels or Kegs, of which the following is a full, clear, and exact description, reference being had to the accompanying drawings, forming part of this specification, in which:

Figure 1 is a top plan view showing one form of my improved sheet metal head.

Fig. 2 is a section on the line II--II of Fig. 1, and showing the head applied to a barrel or keg, and

Figs. 3 and 4 are views similar, respectively, to Figs. 1 and 2, but showing a modification, the section of Fig. 4 being on the line IV--IV of Fig. 3.

My invention is an improvement upon the barrel or keg shown in my Patent No. 914,787, of March 9, 1909. The object of the present invention is to provide a sheet metal head of greatly increased strength, which can be readily manufactured from sheet metal by the use of dies. The invention has particular relation to the method in which the head is reinforced so as to greatly stiffen and strengthen it at the portions thereof which are most likely to give way in service.

Referring first to that form of my invention shown in Figs. 1 and 2, the numeral 2 designates the body of the head, 3 the upwardly extending flange which fits within the head portion of the barrel or keg 4, and 5 the downwardly extending flange fitting around the outer side of the head portion, the whole being formed by suitable die operations from a single piece of sheet metal.

The body portion 2 is preferably dished inwardly, somewhat as shown, and is formed with a star- or spider-shaped reinforcement. This reinforcement is formed by pressing inwardly the central portion of the body to form the central depression 6, with a plurality of spaced radiating depressed ribs 7, which preferably extend to points adjacent to the base of the flange 3.

Experience has shown that the central portion of these heads are most apt to give way in service. This I effectively prevent by the provision of the central reinforce 6, while the radiating ribs 7 stiffen and reinforce the entire body.

The form of my invention shown in Figs.

3 and 4 is similar to that shown in Figs. 1 and 2, except that instead of pressing the metal inwardly to form the central reinforce 6 and the radiating ribs, the operation is reversed and the metal is pressed outwardly, forming these reinforces on the outer surface of the body. Similar reference characters to those used in Figs. 1 and 2 are applied to corresponding parts in Figs. 3 and 4, with the suffix *a*.

In these figures I have also shown the lower edge of the flange 5^a as formed with a rolled bead 8, thus doing away with a raw edge at this point and preventing cracking or splitting of the head when driving it over the chime of the barrel. This bead may also be used on the form shown in Figs. 1 and 2.

It will be noted that in both forms of my invention the body portion is continuously dished across its diameter; and that the central reinforce and the radial reinforcing ribs are pressed out of the general plane of curvature of the dishing. I also preferably taper the radiating ribs so that they will be deepest and widest at the point where they join the central reinforce, with a gradual decrease in both depth and width toward their outer ends.

My invention provides a greatly improved metal head for barrels or kegs which can be manufactured at a relatively small cost by simple die forming operations, and which is strong and durable in service. The need for end hooks for the barrel or keg is done away with, by my combined head and hoop.

I claim:

1. As a new article of manufacture, a barrel or keg head formed from a sheet metal blank and having a top portion dished inwardly across substantially its full diameter, the central portion of the body having the metal thereof pressed out of the general plane of curvature, said head having an annular flange at its outer edge, there being an annular recess of tapered cross section in the flange formed by bending the material upon itself and arranged to receive the chime of the barrel, and the metal being also shaped to form a plurality of hollow tapered radiating ribs the depressions of which open at their inner ends into the depression of the central reinforce, said depressions tapering in width and depth from the central portion toward the edge of the head, substantially as described.
2. As a new article of manufacture, a bar-

- rel or keg head formed from a sheet metal blank and having a top portion dished inwardly across substantially its full diameter, the central portion of the body having 5 the metal thereof pressed out of the general plane of curvature, said head having an annular flange at its outer edge, there being an annular recess of tapered cross section in the flange formed by bending the material 10 upon itself and arranged to receive the chime of the barrel, and the metal being so shaped to form a plurality of hollow tapered radiating ribs the depressions of which open at their inner ends into the depression of the 15 central reinforce, said depressions tapering in width and depth from the central portion toward the edge of the head and said depressions merging into the general plane of curvature of the dished portion adjacent to the 20 edge.
3. A metallic head for staved barrels, kegs and the like, said head being formed from a sheet metal blank dished inwardly over the full diameter of the barrel and having an outwardly flared flange rising from the edge 25 of the dished portion and adapted to fit closely within the chime of the barrel, said flange being bent horizontally outwardly at its outer edge and thence backwardly to form a chime hoop portion, said flange and 30 hoop portion forming a wedging seat for the chime and said flange also forming an abutment to resist outward flexure of the head, substantially as described.

In testimony whereof, I have hereunto set 35 my hand.

JAMES W. BRAINARD.
